[57] **CLAIM**

The ornamental design for a telephone answering service console, as shown and described.

DESCRIPTION

FIG. 1 is a front elevational view of a telephone answering service console showing my new design; FIG. 2 is a top plan view thereof;

FIG. 3 is an elevational view thereof as seen from the right side;

FIG. 4 is an elevational view thereof as seen from the left side;

FIG. 5 is a front elevational view with the subscriber directory boards in downward position, seated against the console top;

FIG. 6 illustrates the configuration of FIG. 5 in top plan view;

FIG. 7 illustrates the configuration of FIG. 5 as seen from the right side; and

FIG. 8 illustrates the configuration of FIG. 5 as seen from the left side.
